US0D1065459S

(12) **United States Design Patent** (10) Patent No.: **US D1,065,459 S**
(45) Date of Patent: ** Mar. 4, 2025

(54) **SPACER**

(71) Applicant: **Graco Minnesota Inc.**, Minneapolis, MN (US)
(72) Inventors: **James R. Ebbin**, Shoreview, MN (US); **Anthony J. Kuschel**, Coon Rapids, MN (US); **Daniel M. Jensen**, Mahtomedi, MN (US); **Bradley G. Kahler**, Otsego, MN (US)

(73) Assignee: **Graco Minnesota Inc.**, Minneapolis, MN (US)

(**) Term: **15 Years**

(21) Appl. No.: **29/854,655**

(22) Filed: **Sep. 27, 2022**

(51) LOC (15) Cl. **23-07**

(52) U.S. Cl.

USPC **D23/259**; D23/262; D8/387
